UNITED STATES PATENT OFFICE

EMIL O. MEHLINE, OF ALAMEDA, CALIFORNIA, ASSIGNOR, BY DIRECT AND MESNE ASSIGNMENTS, TO VICTOR V. KUNKEL, OF OAKLAND, CALIFORNIA

METALLIC TILE

Application filed October 10, 1928. Serial No. 311,508.

This invention relates to tiling for use in interior finish.

It is the principal object of the present invention to provide improved tile of the character described which may be inexpensively manufactured of metal, finished in any desired color and installed on a cementitious or other base.

In carrying out this object I form a tile of sheet metal and lacquer its exposed surfaces in any preferred color. The tile is fitted with means for maintaining it on any suitable base.

One form which the invention may assume is exemplified in the following description and illustrated by way of example in the accompanying drawings in which:

Fig. 1 is a perspective view of the rear side of a tile embodying my invention.

Fig. 2 is a perspective view of the pad which is inserted within the rear of the tile disclosed in Fig. 1.

Fig. 3 is a sectional view taken through a base with the tiling shown in Figs. 1 and 2 mounted thereon.

Fig. 4 is a fragmentary view in perspective of the surface of a wall covered with tile such as disclosed in Figs. 1 and 2.

Fig. 5 is a perspective view disclosing the rear side of another type of tile formed in accordance with my present invention.

Fig. 6 is a central section through a tile such as disclosed in Fig. 5 mounted upon a cementitious base.

Referring more particularly to the accompanying drawings, 10 indicates a tile embodying my invention. This tile is formed of sheet metal and it is here shown as rectangular in shape. However, the tile may be of any preferred geometrical outline without departing from the present invention.

To form the tile a flat sheet of metal is utilized and is cut to the proper dimensions. The peripheral edges of the metal are then bent at right angles to the body portion

thereof as illustrated, giving the tile an appearance of substantial thickness and at the same time finishing the edges. The turned over edges 11 of the tile also stiffen it so that it will be rigid.

In the present application I disclose two methods of mounting the tile on a plane surface. In one of these methods, which is illustrated in Figs. 1 to 3 inclusive, barbed tangs 12 are formed integral with the sheet of metal forming the tile and project rearwardly from the edges of the tile at spaced distances apart. These fastening elements or tangs 12 may be driven into a surface of proper material to properly mount the tile.

In connection with the type of tile shown in Figs. 1 to 3 inclusive I employ a pad 14 of fibrous material having sound deadening and fireproofing qualities. This pad is of dimensions to be snugly received at the rear face of the tile within the turned edges of the same. The thickness of the pad 14 is slightly greater than the depth of the tile so that it will project slightly from the rear thereof. Thus, when the tiling is assembled at a slight distance apart, a key for the cement filling between the edges of the tile will be formed as indicated by the numeral 15 in Fig. 3.

The type of tile 10 disclosed in Figs. 5 and 6 is for use upon a cementitious base. This type of tile is formed with tangs 16 which are bent over parallel to the surface of the tile to secure wire netting or other keying means 17 in place at the rear of the tile. I prefer to use a plurality of layers of netting or other keying material so that a good bond will be established between the tile and the cementitious base upon which it is mounted.

In use, when using the type of tile shown in Figs. 1 to 3 a wood or similar base is provided and the tiles are mounted thereon by driving the tangs 12 into the base. The spaces between the tiles are then filled with

cement which is keyed in as described. The provision of the pad 14 assists in rendering a wall covered by the tiling sound-proof.

When using the tile shown in Figs. 5 and 6, a cementitious base is provided and the tiling is mounted thereon when the cement is in a plastic condition. The cement fills the interior of the tile between the interstices of the keying material and firmly holds the tile in position.

The exposed surfaces of tile here disclosed are properly lacquered in any desired color. This finish is very durable and likewise enables the tile to be produced in any desired color to harmonize with the room in which it is to be used.

It is obvious that the tile here disclosed is inexpensive to manufacture and install.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. As an article of manufacture, a tile formed of metallic material and having foraminous means at its rear surface for securing it to a base, said means consisting of a separate layer of foraminous material attached to the back of the tile and being wholly exposed to be impressed in the base while this is in a plastic state.

2. As an article of manufacture, a tile formed of sheet metal and having an attached layer of foraminous material at its rear surface for securing it to a base, the exposed surface of said tile being of a suitable finish, said layer being fully exposed and adapted to be embedded in a plastic bed to which the tile is to be affixed.

3. A tile unit consisting of a front metal panel body having rearwardly extending marginal portions, and an affixed, interlocking media including exposed transverse and longitudinal elements forming a reticulated layer adapted to be wholly embedded in a plastic base to which the unit is to be applied.

4. A tile unit consisting of a front metal panel body having rearwardly extending marginal portions, and an affixed, interlocking media including exposed transverse and longitudinal elements forming a reticulated layer adapted to be wholly embedded in a plastic base to which the unit is to be applied; said portions having prongs which affix said media in place as a part of the unit in readiness to be applied.

5. A sheet metal tile element provided with means for interlocking it in a plastic bed and comprising rearwardly turned peripheral flanges which have tangs which are bent over substantially parallel to the rear surface of

the tile; said tangs being embedded in the plastic material which fills the space at the back of the embedded tile.

6. A tile having a sheet metal face panel provided with rearwardly bent flanges forming a shallow chamber, and a backing medium disposed in the chamber and being exposed at the back of the panel so as to bear directly against a bed onto which the tile is to be laid; said flanges having fastening prongs provided along their rear edges.

EMIL O. MEHLINE.
